(57) **CLAIM**

The ornamental design for a brewer, as shown and described herein.

DESCRIPTION

FIG. 1 is a top perspective view of a brewer showing a first embodiment our design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof; and

FIG. 7 is a bottom plan view thereof;

FIG. 8 is a perspective view of a brewer showing a second embodiment of our design;

FIG. 9 is a front elevation view thereof;

FIG. 10 is a rear elevation view thereof;

FIG. 11 is a right-side elevation view thereof;

FIG. 12 is a left-side elevation view thereof;

FIG. 13 is a top plan view thereof; and,

FIG. 14 is a bottom plan view thereof.

Color and texture may or may not form part of the claimed design without departing from the design disclosed. The inventors anticipate that the invention can be any part, portion, element, or combination of elements of the depicted design. The addition of further physical elements such as ribs, ridges, textures, and/or dimples are not excluded. Any part, portion, element, or combination of elements of the depicted design or designs which is novel may represent an invention or design for which protection is or may be claimed in the future.

In certain applications of use, embodiments of the brewer can be positioned on a counter, a shelf, a rack, or a table and can be used to create cold, ambient, and/or hot brewed beverages such as coffee or tea. Embodiments of the brewer can be made of a variety of materials including, but not limited, to plastic or metal, and certain portions of the BREWER can be transparent.
